UNITED STATES PATENT OFFICE.

FRED W. LEUTHESSER, OF CHICAGO, ILLINOIS, ASSIGNOR TO MONASH-YOUNKER COMPANY, OF CHICAGO, ILLINOIS, A CORPORATION OF ILLINOIS.

AIR-VALVE FOR RADIATORS.

No. 852,383.

Specification of Letters Patent.

Patented April 30, 1907.

Original application filed April 5, 1902, Serial No. 101,475. Divided and this application filed March 24, 1904. Serial No. 199,825.

To all whom it may concern:

Be it known that I, FRED W. LEUTHESSER, a citizen of the United States, residing at Chicago, in the county of Cook and State of Illinois, have invented certain new and useful Improvements in Air-Valves for Radiators, of which the following is a specification, the same being a division of my application, Serial No. 101,475, filed April 5, 1902.

This invention relates to that form or type of air valves for radiators in which a hollow member or stem, contractible under the influence of cold and expandable under the influence of heat, furnishes the means for shutting off the outflow of air and the water of condensation when the same is expanded and permitting such outflow of air and water of condensation when the expandable member or stem is contracted.

The objects of the invention are to fixedly and firmly secure the expandable member or stem at its lower end in the shell or casing of the valve and have the connection one by which the lower end of the chamber in which the expandable member or stem operates is positively and effectually sealed by the entering of the lower end of the expandable member or stem in its fixed position in the lower end of the shell or casing, so that in connection with an adjustable plug having a seating wall or face to coact with the seating end of the expandable member or stem, the chamber of the shell or casing in which the member or stem operates is sealed, thus insuring the maintaining of a vacuum within the chamber of the shell or casing; to enable the movable or adjustable plug to be changed in its correlation to the acting end of the expandable member or stem without disturbing

the vacuum in the chamber of the casing or shell and without disconnecting the valve from the coupling connecting the valve as a whole with the drain or return pipe for the water of condensation; and to improve generally the construction and arrangement of the several elements which enter into the formation of the valve as a whole.

The invention consists in the features of construction and combinations of parts hereinafter described and claimed.

In the drawings Figure 1 is an elevation of the valve of the invention assembled ready for use; Fig. 2 a sectional elevation of the valve shown in Fig. 1; Fig. 3 a cross section

on line 3 of Fig. 2 looking in the direction of 55 the arrow with the closing cap removed; Fig. 4 a cross section on line 4 of Fig. 2 looking in the direction of the arrow; Fig. 5 a detail in sectional elevation, showing the lower end of the valve shell or casing and the manner of forming a sealed joint for the lower end 60 of the expandable member or stem; and Fig. 6 an elevation of the expandable member or stem and its socket support.

The shell or casing for the valve is made of 65 metal and is formed with a central portion or body A, a lower portion or neck end A' and an upper portion or head A², leaving a chamber A³ within the body between the neck and head ends into which chamber a passage a' 70 extends through a nipple a leads, furnishing communication between the chamber of the shell or casing and the radiator, when the nipple is entered into the wall of the radiator as usual. The neck A' has an exterior screw 75 thread and the head A² has a wall or rim a' with an exterior screw thread, and the head has an interior screw thread. The nipple a is for an attachment of the valve as a whole 80 to a radiator and the passage a' furnishes an outlet from the radiator into the chamber A³ of the shell or casing, so that the air and the water of condensation can enter the chamber of the valve from the radiator to escape from the valve, when the passageway in the valve 85 for the escape is open.

The expandable member or stem B can be made of vulcanite or other material having the adaptability of expanding under heat and contracting under cold. This member or 90 stem has a central longitudinal passage b, for the eduction of air and the water of condensation when the member or stem is contracted so as to open communication with the chamber A³ of the shell or casing. The 95 body of the member or stem is circular in cross section and its upper or acting end b', as shown is tapered and forms a plug or seating end to engage a seating wall or face on the adjustable seat which coacts there- 100 with.

The seat for the plug or acting end b' of the expandable member or stem is in the form of a plug C, having an exterior screw thread engaging the interior screw thread of 105 the head A², so as to make a sealed joint around the plug C when entered into the interior of the head A², sealing the chamber A³

at its upper end against the escape of air and the water of condensation. The under face of the plug C has therein an opening c with a tapered portion c' , forming a wall or seat to 5 coat with the tapered plug or acting end of the expansible member or stem, so that with the advance of the member or stem by expansion, the face of the plug or acting end will engage the face of the seating wall c' and 10 close communication between the chamber A^3 and the eduction passage b of the member or stem, closing the valve against the escape of the air and the water of condensation. The plug C is to be adjusted so that its seating 15 under face will properly coat with the seating end of the expansible member or stem; and for turning the plug C into its proper advanced or receded position the upper face thereof has a cross nick c^2 for receiving the end of a screw driver or other implement by means of which the plug C can be turned as required. The adjustment of the plug C is to be one that will cause the 20 expansible member or stem, when expanded under the effects of heat, to engage the seating face of the plug and close communication between the chamber A^3 and the passage b , and when contracted under the effects of 25 cold have the acting end of the expansible member or stem withdrawn from the coacting seating face of the plug C to open communication between the chamber A^3 and the eduction passage b , allowing the air and the water of condensation to escape through the eduction passage b . The expansible member or 30 stem is shown in its expanded position in Fig. 2 of the drawing and in engagement with the seating wall of the adjustable plug.

The upper end of the shell or casing is 40 closed against access to the seating plug by a cap D having an exterior screw thread and entered into the rim or wall a^2 of the head A^2 of the shell or casing. The under face of the cap D, in the construction shown, has an annular projecting portion d with an inclined peripheral face to receive a packing ring d' or gasket d' , which ring or gasket impinges against an inclined face a^3 on the interior of the head A^2 , when the closing cap D is entered into the wall a^2 , making a tight joint between the closing cap D and the rim or wall a^2 , which furnishes additional sealing of the upper end of the shell or casing against the escape of the air and the water of condensation, thus making assured the maintaining 50 of a vacuum in the chamber A^3 , after such vacuum has been once established. The closing cap D, as shown, has in its upper face holes d^2 for the engagement of a suitable 55 turnkey by which the cap can be entered into and removed from the shell or casing, and when entered the advance of the closing cap should be sufficient to compress the packing d' and form a tight joint for the upper 60 end of the shell or casing.

The exterior screw thread on the neck A' has entered thereonto a coupling nut E, having an inwardly extending lip or flange e to engage a circumferential flange f on a coupling nipple F, for attaching the coupling nipple 70 to the shell or casing, the coupling nipple serving as a medium for connecting the valve with a return or drain pipe, not shown; and when the valve is connected the breaking of the coupling, for the purpose of adjusting the 75 relation between the expansible member or stem and its coacting seat, is not required as the adjustment can be made from the upper end of the shell or casing by turning the seating plug and such turning of the seating plug 80 will not destroy the established vacuum for the valve.

The lower end of the expansible member or stem is entered into a socket support G, having a central tube g which enters a hole 85 therefor in the lower end of the expansible member or stem so as to bring the eduction passage b of the member or stem and the passage in the tube g in line one with the other and making a continuous passage through 90 the member or stem and the socket support therefor, as shown in Figs. 2 and 5. The socket support G has an annular rim or wall g' , into which is entered the lower end of the expansible member or stem and the upper 95 edge g^2 of this rim or wall g' is inwardly turned and entered into an annular recess b^4 in the body of the expansible member or stem, locking the member or stem to the socket and making a contact between the exterior of the expansible member or stem and the interior of the annular rim or wall. The 100 annular rim or wall g' of the socket support is entered into an opening therefor in the lower end a^4 of the shell or casing by forcing 105 the rim or wall into its receiving hole, or otherwise entering the rim or wall g' into the wall a^4 in such manner as to make a tight joint between the face of the annular rim or wall g' and the face of the wall a^4 of the shell 110 or casing, which joint will atmospherically seal the chamber A^3 at its lower end, so that, when the expansible member or stem in the chamber A^3 is lengthened, the chamber will 115 be atmospherically sealed at its top and bottom so as to maintain a vacuum when once established. The under face of the socket support G has a depending circumferential flange g^3 , with an inclined inner face against 120 which face the end of the annular rim f' on the coupling nipple F will abut, when the coupling nut is entered onto the lower end or neck end of the shell or casing. The exterior face of the annular rim f' or end of the coupling F is curved, in the construction shown, 125 so as to insure a close contact of its face with the corner edge of the depending flange g^3 , making a tight joint between the end of the coupling nipple and the under face of the socket support, when the valve is assembled 130

ready for use. The engagement of the corner edge of the flange g^3 with the face of the coupling nipple serves to force the socket support into the contacting wall of the shell or casing and to insure the contact or impingement of a shoulder g^4 on the socket support with a shoulder g^5 on the lower end of the wall a^4 , which further insures a positive atmospheric or hermetical seal of the lower end of the chamber A^3 against the escape of air and the water of condensation, and also assists in maintaining the vacuum in the chamber A^3 when once established.

The construction of the valve, as a whole, is one by which the adjustment of the seating face for the expansible member or stem and the seating plug is attained without breaking the coupling of the valve to the drain or return pipe; and at the same time the construction is one which enables the expansible member or stem to be withdrawn bodily for repairs or otherwise by removing the coupling nut and coupling nipple, so that the expansible member or stem can be withdrawn through the opening left by the withdrawal of the nut and nipple.

What I claim as new and desire to secure by Letters Patent is:

1. In an air valve for radiators, the combination of a shell or casing having a chamber therein with an opening at each end of the chamber and an inlet leading into the chamber between its ends, an expansible member or stem having an acting or seating upper end, a socket snugly entered into the lower end of the shell or casing at the terminus of the lower end of the chamber and having fixedly secured therein the lower end of the expansible member or stem, the socket having a depending flange on its under face and when inserted tightly and atmospherically closing the opening at the lower end of the chamber of the shell or casing, an adjustable seat for the acting or seating end of the expansible member or stem, located and movable within the upper end of and below and clear of the top of the shell or casing, and when in place tightly and atmospherically closing the opening at the upper end of the chamber of the shell or casing, with a space at the top of the shell or casing above the adjustable seat, a coupling nut entered onto the lower end of the shell or casing, a coupling nipple carried by the nut and entered into the lower end of the shell or casing and engaging the depending flange of the socket and effecting an additional seal for the lower end of the chamber, and a removable closing and sealing cap entered into the interior of and engaged with the upper end of the shell or casing and located above the adjustable seat for effecting a double sealing at the upper end of the chamber of the shell or casing and enabling access to be had to the adjustable seat without breaking the seal of the adjustable seat, substantially as described. 95
3. In an air valve for radiators, the combination of a shell or casing having a chamber therein with an opening at each end of the chamber the wall forming the lower opening having formed therein an under cut shoulder, an inlet leading into the chamber between its ends, an expansible member or stem, located in the chamber and having an acting or seating upper end, and a socket having fixedly secured therein the lower end of the expansible member or stem, the socket having a rim or wall to enter and engage with a wall of the shell or casing and having an enlarged lower end forming a shoulder adapted to engage from below the under cut shoulder on the wall of the shell or casing, for the socket with its shoulder, the stem, and the wall of the shell or casing with its shoulder to tightly close and furnish an atmospheric seal for the opening at the lower end of the chamber of the shell or casing, substantially as described. 105
4. In an air valve for radiators, the combination of a shell or casing having a chamber therein with an opening at each end of the chamber and an inlet leading into the chamber between its ends, an expansible member or stem located in the chamber and having an acting or seating upper end, a socket having fixedly secured therein the lower end of the expansible member or stem the socket having a rim or wall to enter and engage with a wall of the shell or casing and 110
2. In an air valve for radiators, the combination of a shell or casing having a chamber therein with an opening at each end of the chamber and an inlet leading into the chamber between its ends, an expansible member or stem having an acting or seating upper 120
- 65

end, a socket snugly entered into the lower end of the shell or casing at the terminus of the lower end of the chamber and having fixedly secured therein the lower end of the expansible member or stem, the socket having a depending flange on its under face and when inserted tightly and atmospherically closing the opening at the lower end of the chamber of the shell or casing, an adjustable seat for the acting or seating end of the expansible member or stem, located and movable within the upper end of and below and clear of the top of the shell or casing, and when in place tightly and atmospherically closing the opening at the upper end of the chamber of the shell or casing, with a space at the top of the shell or casing above the adjustable seat, a coupling nut entered onto the lower end of the shell or casing, a coupling nipple carried by the nut and entered into the lower end of the shell or casing and engaging the depending flange of the socket and effecting an additional seal for the lower end of the chamber, and a removable closing and sealing cap entered into the interior of and engaged with the upper end of the shell or casing and located above the adjustable seat for effecting a double sealing at the upper end of the chamber of the shell or casing and enabling access to be had to the adjustable seat without breaking the seal of the adjustable seat, substantially as described. 125

130

having a shoulder at the start of the rim or wall to engage from below a shoulder on the wall of the shell or casing, for the socket with its shoulder, the stem, and the wall of the shell or casing with its shoulder to tightly close and atmospherically seal the opening and the lower end of the chamber of the shell or casing, and an adjustable seat for the acting or seating end of the expandible member or stem, located and movable in the open upper end of and below and clear of the shell or casing, and when in place closing and atmospherically sealing the opening at the upper end of the chamber of the shell or casing, substantially as described.

5. In an air valve for radiators, the combination of a shell or casing having a chamber therein with an opening at each end of the chamber and an inlet leading into the chamber between its ends, an expandible member or stem located in the chamber and having an acting or seating upper end, a socket having fixedly secured therein the lower end of the expandible member or stem,

the socket having on its under side a depending flange with an inner contact edge and having a rim or wall to enter and engage with a wall of the shell or casing and having a shoulder at the start of the rim or wall to engage from below a shoulder on the wall of the shell or casing, for the socket with its shoulder, the stem, and the wall of the shell or casing with its shoulder to tightly close and atmospherically seal the opening and the lower end of the chamber of the shell or casing, a coupling nut entered onto the lower end of the shell or casing, and a coupling nipple entered into the coupling nut and having a bearing end to engage with the contact edge of the depending flange of the socket, making a joint for effecting an additional atmospheric sealing for the chamber of the shell or casing at its lower end, substantially as described.

FRED W. LEUTHESER.
